UNITED STATES PATENT OFFICE.

HENRY BUSSE, OF WILLIAMSPORT, PENNSYLVANIA, ASSIGNOR TO CHARLES R. HARRIS, OF SAME PLACE.

DESIGN FOR A BICYCLE-FRAME.

SPECIFICATION forming part of Design No. 27,187, dated June 8, 1897.

Application filed April 14, 1897. Serial No. 632,185. Term of patent 14 years.

To all whom it may concern:

Be it known that I, HENRY BUSSE, a citizen of the United States, residing at Williamsport, in the county of Lycoming and State of Pennsylvania, have invented and produced a new and original Design for Bicycle-Frames, of which the following is a specification, reference being had to the accompanying drawing, forming a part thereof.

10 The accompanying drawing illustrates my design.

The leading feature of my design consists in a bicycle-frame, the rear portion of which is circular in outline, with the rear wheel bearing eccentrically located therein.

15 A represents the steering-head, and B the frame. Starting at point 1 on the steering-head the frame extends rearward in a gradual downward curve or sweep to a point approximately below the rear axle and then upward and around in the outline of a circle 2.

A bearing 3 for the axle of the rear wheel is eccentrically located within this circle. Another bar 4 of the frame starts at point 5 on the steering-head, a short distance above the 25 point 1, and extends rearward and downward, joining the main frame at point 7, after which it extends upward, joining the main frame again at point 8 and terminating in the seat-socket 9.

30 In the space formed in the frame forward of circular rear portion the bearing 10 is located, it being secured to the three surrounding parts of the frame.

What I claim is—

35 The design for bicycle-frames substantially as herein shown and described.

HENRY BUSSE.
